COMBINED DOOR HANDLE AND BRACKET

Robert G. Williams, Oakland, Calif., assignor to
Milton L. Sturm, doing business as Milton
Sturm & Company, Chicago, Ill.

Original design application January 26, 1946, Se-
rial No. 126,030. Divided and this application
May 18, 1949, Serial No. 2,730

Term of patent 3½ years

(Cl. D10—8)

To all whom it may concern:

Be it known that I, Robert G. Williams, a citizen of the United States, residing at Oakland, California, have invented a new, original, and ornamental Design for a Combined Door Handle and Bracket, of which the following is a specification, reference being had to the accompanying drawing, forming a part thereof.

This application is a division of my copending application, Serial No. D. 126,030, filed January 26, 1946, which is now abandoned.

In the drawing:

Figure 1 is a front view of a combined door handle and bracket, embodying my new design; and

Figure 2 is a side view thereof.

The characteristic features of the design reside in the bracket portion shown in full lines.

I claim:

The ornamental design for a combined door handle and bracket, substantially as shown and described.

ROBERT G. WILLIAMS.
